(57) **CLAIM**

The ornamental design for a shoe sole with pattern, as shown and described.

DESCRIPTION

FIG. 1 is a bottom perspective view of a shoe sole with pattern, showing the new design;

FIG. 2 is a bottom plan view thereof;

FIG. 3 is a front elevational view thereof;

FIG. 4 is a rear elevational view thereof; and,

FIG. 5 is a right-side elevational view thereof, the left-side elevational view being a mirror image thereof.

The broken lines showing a shoe upper in the figures depict environmental matter, and form no part of the claimed design. The first embodiment is a shoe sole with pattern for the left-footed shoe, which has been shown in the figures, it being understood that a second embodiment is a shoe sole with pattern for the right-footed shoe, which is a mirror image of the figures depicted. The top elevational view of the shoe sole with pattern is not ornamental, and forms no part of the claimed design.
